UNITED STATES PATENT OFFICE.

WILLIAM R. BLOWERS, OF TORONTO, ONTARIO, CANADA.

DESIGN FOR A TIRE.

44,164.

Specification for Design.

Patented June 10, 1913.

Application filed December 14, 1912. Serial No. 736,851. Term of patent 3½ years.

To all whom it may concern:

Be it known that I, WILLIAM R. BLOWERS, a citizen of the United States of America, and resident of the city of Toronto, county of York, Province of Ontario, in the Dominion of Canada, have invented a new, original, and ornamental Design for a Tire, of which the following is a specification.

Figure 1 is a perspective view of a portion of a tire casing constructed in accordance with my design. Fig. 2 is a plan view of a portion of a tire constructed in accordance with my design.

The said design consists in the arrangement of a circumferential rib in the median plane of the tire and a plurality of substantially V-shaped ribs extending laterally from each side of the central rib and gradually

merging to the rounded surface of the tire casing. The apexes of the V-shaped ribs on one side of the center rib point in the opposite direction to the ribs on the opposite side. The apexes of the V-ribs are each formed with a rounded knob formed with beveled edges beveled to correspond with the beveled edges of the V-shaped ribs.

What I claim is:

The ornamental design for a tire as shown and described.

Signed at the city of Toronto, county of York, Province of Ontario, in the Dominion of Canada, this 12th day of December 1912.

WILLIAM R. BLOWERS.

Witnesses:

R. S. CHILTON,
E. HERON.
